(57) **CLAIM**

The ornamental design for a novelty lamp, as shown and described.

DESCRIPTION

FIG. 1 is a perspective view of my novelty lamp, showing my new design;

FIG. 2 is a top plan view of the design;

FIG. 3 is a front elevational view thereof, the left side elevational view, right side elevational view, and rear elevational view being identical thereto;

FIG. 4 is a bottom plan view thereof;

FIG. 5 is a perspective view of an alternate embodiment of my new design; and,

FIG. 6 is a front elevational view of the alternate embodiment, the left side elevational view, right side elevational view, and rear elevational view being identical thereto.
